WELT SHOE AND TWO-UNIT WELTING

Filed March 29, 1928

INVENTOR:

Harry Lyon
BY Marvin J. Cullen
his ATTORNEY

UNITED STATES PATENT OFFICE.

HARRY LYON, OF HOLBROOK, MASSACHUSETTS, ASSIGNOR TO PERLEY E. BARBOUR,
TRADING AS BARBOUR WELTING COMPANY, OF BROCKTON, MASSACHUSETTS.

WELT SHOE AND TWO-UNIT WELTING.

Application filed March 29, 1928. Serial No. 265,678.

This invention relates to welt shoes and particularly to two unit welting therefor of the kind for giving a "heavy edge" effect to the shoe in which it is used.

5 Heretofore it has been the general practice to produce a heavy edge on a shoe by adding an intermediate sole and outseaming both soles to a Goodyear welt. The general object of the present invention is to provide the same 10 heavy edge on the shoe by a specially formed two-unit welt outseamed to the usual outsole only, thereby saving the very considerable expense of the intermediate sole. There is ample wear in a single sole, in fact with 15 the double soled shoe re-soling is demanded by the owner upon wearing through to the intermediate sole, so that this invention gives all the advantages heretofore attained but with much less sole leather and the consequent saving of this expensive stock. Further 20 objects of the invention are to produce heavy edged welting from two units in an economical manner while preserving the extension, retaining the "shape insurance" ad- 25 vantages of certain types of beaded Goodyear welting, providing for an economical use of bottom filler notwithstanding the dou- 30 bling of the thickness of the welt, and pro- 35 ducing a welt that, while giving the shoe a heavy edge, will enable the welt sewing ma- 40 chine operator to sew just as strong an inseam as may be served with the ordinary Goodyear welting.

To the accomplishment of these objects and 35 such others as may hereinafter appear, the invention comprises the features of construction and combinations of parts hereinafter described and then particularly pointed out in the appended claims.

40 The simplest form of the invention known to me is illustrated in the accompanying drawing, all the views being in perspective, and in which Figure 1 is a view of a portion of a strip of Goodyear welting to be used as the base or bottom unit; Fig. 2 is a view of a portion of the strip forming the top unit; Fig. 3 is a view of the finished welting; and Fig. 4 is a view of a portion of a Goodyear shoe having a single outsole and the welt of this 45 invention embodied therein.

In the embodiment of the invention illustrated in the drawing the heavy edge effect is produced by building up one strip of welt material on another with due allowance for 50 a light or thin enough inner margin to per-

mit easy handling at the inseam sewing operation. Accordingly 10 (Fig. 1) is a strip having the characteristics of Goodyear welting, i. e. a groove 12 and a bevel 13 preferably, but not necessarily, on the lower corner. 60 The Goodyear strip 10 forms the base or bottom unit and the heavy edge is obtained by placing on the exposed face of the strip 10 a top unit 14 (Fig. 2) the characteristic feature of which is a wedge-shaped inner end 65 that is illustrated as a sloping or oblique surface 15 forming, in the welt, a substantial inwardly facing shoulder. It is preferred that the width of the top unit 14 be somewhat less than the width of the bottom unit 10 so as to 70 provide for a sufficient width of thinner inner margin 16 (Fig. 3) to render the welting completely flexible for inseam sewing. If the welting is to be handled as a unitary piece then the two units 10 and 14 are cemented 75 together, care being taken when doing this that the outer edge of the top unit extends to the outer edge of the bottom unit. The two units are preferably assembled with their outer edges flush since this prevents undue 80 waste of either in later trimming operations on the sole edge. It will be seen from Fig. 4 that the upwardly and outwardly sloping inner edge of the top unit 10 lies above the stitch-receiving groove 12.

85 When sewed into the shoe the inseam stitches 18 (Fig. 4) pass through the thinner margin 16, just inside the wedge end 15 in the illustrated embodiment, and those skilled in the art will recognize that, notwithstanding its greater outer edge bulk, the novel welting can be sewed to the insole 20 just as tightly as the simple Goodyear type. The inseam draws the welt in place with the wedge end 15 seated snugly in the crease between the 90 Goodyear welt 10 and the upper 22, pressing the upper materials at this point against the edge of the insole 20. The top unit 14 is securely held in this position by the outseam 24 which unites the welt to the outsole 26.

95 It will be seen from Fig. 4 that the base unit 10 lies in the same position as a regular Goodyear welt with relation to the insole. Hence this shoe requires no additional sole filler 28. The support given to the upper about 100 the edge of the insole insures a retention of the shape of the shoe and prevents "running over" due to collapse of the margin of the insole which may occur because of wetting or cracking when either too punky or too brittle stock 110

is used. The fact that the top unit 14 extends so far outward that it actually forms a part of the sole edge, and is held by the outseam, gives it such strength that the position in which it is originally placed never varies during wear, in contradistinction to the so-called "cork-sole" welts comprising a narrow bead that are difficult to draw snugly into the crease and must be forced into place by a subsequent hammering or pounding. Wetting the shoe margin is almost sure to cause the bead of a cork-sole welt to gape, but the greater bulk and permanent securement of the top unit of the heavy edged welt of this invention wholly overcomes this defect.

The two units may be fed separately to the shoe during its manufacture. The unit 10 may be fed into position at the inseaming operation and the unit 14 may be fed into position at the outseaming operation. Whether handled as a unit or separately is a matter of choice for the manufacturer.

The shape and proportions of the two units may be varied within the skill of the artisan without departing from the true scope of the invention as defined by the appended claims.

The nature and scope of my invention having been indicated, and its simplest embodiment and application to a shoe having been specifically described, what is claimed as new, is:—

1. Two unit welting having top and bottom units of strip material assembled with their outer edges flush and having an inner margin thinner than the outer margin for receiving

inseam stitching, said top unit presenting a substantial inwardly facing shoulder above said thinner inner margin.

2. Two unit welting comprising a bottom unit of full welt width having a stitch-receiving groove, a top unit of less width than the bottom unit having its outer edge flush with the outer edge of the bottom unit and its inner edge sloping upwardly and outwardly, said inner edge lying above said stitch-receiving groove.

3. Shoe welting comprising a base unit consisting of a strip of Goodyear welting and a second unit consisting of a strip applied to the exposed face of the Goodyear welting, having an inner edge substantially wedge-shaped to fit into the crease formed between the Goodyear welt and upper of a shoe and having an outer edge located to form a part of the finished shoe sole edge when incorporated in a shoe.

4. A welt shoe having upper materials and an insole, a two unit welt having its bottom unit inseam stitched to said insole through the upper materials and its top unit extending outwardly to the outer edge of the bottom unit to form a part of the sole edge and having an oblique shoulder at its inner end that is held by the inseam stitches pressed against the upper materials that embrace the edge of said insole, and an outsole secured to the welt by stitching through both units whereby the top unit is securely held in its position of pressure against the edge of the insole.

HARRY LYON.
